DESIGN FOR A CUP

William Dolphin, Chicago, Ill.

Application December 16, 1939, Serial No. 88,935

Term of patent 14 years

To all whom it may concern:

Be it known that I, William Dolphin, a citizen of the United States of America and resident of Chicago, county of Cook, and State of Illinois, have invented a new, original, and ornamental Design for a Cup, of which the following is a specification, reference being had to the accompanying drawing, forming a part thereof, wherein

Fig. 1 is a side elevational view of the cup, showing my design;

Fig. 2 is a top plan view, and

Fig. 3 is a vertical sectional view, taken on the line 3—3 of Fig. 2.

What I claim is:

The ornamental design for a cup, as shown.

WILLIAM DOLPHIN.
